UNITED STATES PATENT OFFICE

155,596

DESIGN FOR A FRONT FOR A SPECTACLE FRAME

Joseph Gaspari, Rye, N. Y.

Application August 28, 1947, Serial No. 141,103

Term of patent 3½ years

(Cl. D57—1)

To all whom it may concern:

Be it known that I, Joseph Gaspari, a citizen of the United States, residing in Rye, in the county of Westchester, State of New York, have invented a new, original, and ornamental Design for a Front for a Spectacle Frame, of which the following is a specification, reference being had to the accompanying drawing, forming a part thereof.

In the drawing:

Figure 1 is an elevational view of a front for a spectacle frame, showing my new design.

Figure 2 is a top plan view thereof; and
Figure 3 is a side view thereof.

I claim:

The ornamental design for a front for a spectacle frame, as shown.

JOSEPH GASPARI.
